UNITED STATES PATENT OFFICE.

MARTIN ROHMER, OF GERSTHOFEN, NEAR AUGSBURG, GERMANY, ASSIGNOR TO
FARBWERKE VORM. MEISTER LUCIUS & BRUNING, OF HÖCHST-ON-THE-MAIN,
GERMANY, A CORPORATION OF GERMANY.

PROCESS OF PRODUCING NITROGEN SIMULTANEOUSLY WITH OXIDS OF NITROGEN.

1,253,534.

Specification of Letters Patent. Patented Jan. 15, 1918.

No Drawing.

Application filed April 16, 1914. Serial No. 832,236.

To all whom it may concern:

Be it known that I, MARTIN ROHMER, Ph. D., chemist, a citizen of the Empire of Germany, residing at Gersthofen, near Augsburg, Germany, have invented certain new and useful Improvements in Processes of Producing Nitrogen Simultaneously with Oxids of Nitrogen, of which the following is a specification.

- 10 In U. S. Patent 1,096,392 patented May 12, 1914, I have described a process for producing nitrogen simultaneously with oxids of nitrogen by burning ammonia in atmospheric air, the characteristic feature of
15 which is that there is no excess of oxygen in the reacting mixture of air and ammonia of high concentration, so that, after the separation of lower or higher oxids of nitrogen, pure atmospheric nitrogen is obtained.
20 In the course of my further researches on the subject-matter of the above invention, I have found that there may also be used combustion air with a higher percentage of oxygen than corresponds to atmospheric air,
25 while maintaining the same proportion of ammonia and oxygen as is essential in the process described in the aforesaid patent.

This process offers some particular advantages if it is intended to obtain the oxids 30 of nitrogen, which are produced simultaneously with atmospheric nitrogen, in concentrations which are still higher than in the aforesaid patent.

For instance the proportion stated in Example II of that patent, viz. 12.3 parts by volume of ammonia-gas to the oxygen contained in 87.7 parts by volume of air, may also be obtained by substituting for this air oxygen in any desired degree. In this case 35 the limit of the proportion is 2 parts by volume of ammonia gas to 3 parts by volume of oxygen. Such gas-mixture is of an explosive character; however by replacing only about half of the combustion air by oxygen any danger of explosion is removed as it is, for instance, when using a mixture 40 of 12.3 parts by volume of ammonia-gas

and only 40 parts by volume of air and 10 parts by volume of oxygen or, what amounts to the same, 50 parts by volume of an air 50 richer in oxygen and containing 36.8 per cent. of oxygen. By substituting oxygen for the air to a still greater extent and thus increasing the percentage of oxygen, the mixture of ammonia, air and oxygen becomes 55 inflammable and precautions must be taken to prevent the flame from being thrown back into the mixing vessels.

When a mixture of the above proportion of ammonia to oxygen is burned, nitric oxid 60 (NO) is obtained in a very good yield and an extremely high concentration. After cooling, the quantity of the residual oxygen is sufficient only for the conversion of one half of the nitric oxid (NO) into nitrogen 65 tetroxid. Thus, a mixture of nitric oxid (NO) and nitrogen tetroxid (N_2O_4) is produced, which mixture, when further cooled, forms nitrogen trioxid (N_2O_3). By absorption in caustic soda lye, the latter is most 70 easily and completely converted into the valuable sodium nitrite, and the escaping gases will be pure atmospheric nitrogen.

The present process may, of course, be carried out also with a higher pressure. 75 Then, the proportion of ammonia to oxygen being for instance two volumes of ammonia gas to three and a half volumes of oxygen, there is directly obtained, without strong refrigeration, nitrogen tetroxid in liquid 80 condition, since in this case the oxygen remaining after the combustion of the ammonia secondarily oxidizes the whole of the nitric oxid, as described in the aforesaid Patent No. 1,096,392, Example I, and the 85 modification thereof according to Example IV.

Having now described my invention what I claim is:

1. The process of producing nitrogen and 90 oxids of nitrogen, which consists in burning ammonia in presence of oxygen and nitrogen, the proportion of oxygen to nitrogen being higher than in atmospheric air, the

reaction mixture containing a high percentage of ammonia, and just sufficient oxygen to oxidize the hydrogen-component of the ammonia to water and its nitrogen-component to lower or higher oxids of nitrogen.

2. The process of producing nitrous gases which consists in providing a mixture of oxygen, air and ammonia containing sufficient oxygen to sustain the reaction, and sub-

jecting said mixture to the action of a hot 10 catalyst, substantially as described.

In testimony whereof I affix my signature in presence of two witnesses.

MARTIN ROHMER.
